ABSTRACT

The deactivation rate for a supported HF-antimony pentafluoride catalyst, used in a process for isomerizing C_5 , C_6 , or C_7 normal paraffin at low temperature, is sharply reduced by including sufficient isobutane in the feed so that the feed isobutane content is more than 25 weight per cent.

ISOMERIZATION
CROSS REFERENCE TO RELATED
APPLICATIONS

This application is a continuation-in-part of U.S. patent application Ser. No. 268,296, filed July 3, 1972 now abandoned.

BACKGROUND OF THE INVENTION

The present invention relates to the isomerization of paraffins using a hydrogen fluoride-antimony pentafluoride catalyst, at low temperatures such as below 400°F., especially below 120°F.

The present invention is particularly directed to what may be called ultra low temperature isomerization. Thus reference below is made briefly to isomerization in general and then especially to ultra low temperature isomerization.

Isomerization of normal paraffins such as n-pentane, n-hexane or n-heptane is widely practiced for production of higher octane isomers for use in gasoline.

Table 1 below shows the incentive for isomerization.

TABLE 1.

Hydrocarbon	Research octane		Motor octane	
	Clear	3 cc TEL	Clear	3 cc TEL
n-Pentane	62	89	62	84
i-Pentane	92	109	90	105
n-Hexane	25	65	26	65
2-Methylpentane	73	93	74	91
3-Methylpentane	75	93	74	91
2,2-Dimethylbutane (neohexane)	92	106	93	113
2,3-Dimethylbutane (diisopropyl)	103	119	94	112

Isomerization processes can be divided into high, low, and ultra low temperature processes. Rough temperature ranges are: 500°-800°F. for high temperature isomerization; 150°-400°F. for low temperature isomerization; and -50°F. to 150°F. for ultra low temperature isomerization. In the past, commercial operation for low temperature isomerization typically has utilized a catalyst containing AlCl_3 .

In typical high temperature isomerization, a pentanehexane feed, combined with a normal pentane recycle stream, is fractionated to take i-pentane overhead. The fractionator bottoms are mixed with hydrogen, preheated, and charged to a reactor. Reactor effluent is cooled and flashed to separate recycle hydrogen from the product, which is stabilized and then depentanized, the pentanes being recycled to the deisopentanizer. i-Pentane overheads from the deisopentanizer and the i-hexane bottoms from the depentanizer constitute the product.

Typical reaction conditions are:

Catalyst	Pt on Al_2O_3 or $\text{Al}_2\text{O}_3\text{-SiO}_2$
Temperature, °F	700-900
Pressure, psi	300-700
Space velocity, wt/hr/wt	1-6
H_2 recycle, mole/mole	2-6
Halide promoter	yes, if base is Al_2O_3
Regeneration	Steam-air

For typical low temperature isomerization the catalyst used is AlCl_3 plus hydrogen chloride. Low tempera-

ture isomerization feed stock, dried and preheated to reaction temperature, is combined with a recycle stream (if recycling is practiced), mixed with hydrogen chloride, and passed through a reactor and an aluminum chloride recovery section. Reactor effluent is cooled and flashed to discharge any light gases through a small absorber that recovers hydrogen chloride carried off in the gases. Liquid from the flash drum is stripped to recover hydrogen chloride, and is caustic-washed to remove the last traces of acid. The stripping column is usually operated at a pressure high enough that the stripped hydrogen chloride can be returned directly to the reactor. If recycling of unconverted normal paraffin is practiced, the recycle stream is then fractionated from the product.

Typical reaction conditions are:

Catalyst	$\text{AlCl}_3\text{-HCl}$
Inhibitor	H_2 (60 psi)
Pressure, psi	300
Temperature, °F	176-212
Space Velocity, V/hr/V	1.0-2.5
HCl conc., wt%	5
Conversion %	60

Ultra low temperature isomerization so far has not been commercially employed. However, there is considerable incentive to develop a commercially attractive low temperature isomerization process because the lower the temperature the more favorable is the equilibrium for isoparaffin relative to normal paraffins. Ultra low temperatures are especially attractive for substantial production of the very high octane dimethyl butanes.

U.S. Pat. No. 2,956,095 describes an ultra low temperature isomerization process employing a fluosulfonic acid catalyst instead of a Friedel-Crafts type catalyst such as AlCl_3 . According to the U.S. Pat. No. 2,956,095, process reaction conditions include a temperature between 32° and 80°F., pressure between 0 and 50 psig, and added hydrogen of 0-200 cubic feet per barrel of feed. The process of the U.S. Pat. No. 2,956,095 also employs a compound capable of forming a stable carbonium ion as part of the catalyst system. Preferably tertiary butyl alcohol is used as the favored compound to form a stable carbonium ion; the tertiary butyl alcohol is said in the patent to be a carbonium ion "activator".

Since the reaction mechanism for isomerization is thought to involve carbonium ions it is of course desirable to have a species that will form carbonium ions to start isomerization reaction chains. Isomerization reaction mechanisms are discussed in chapter 28 by Pines and Hoffman in "Friedel-Crafts and Related Reactions," Vol. 2, Edited by G. A. Olah, Interscience Publishers (1964); see especially p. 1223.

U.S. Pat. No. 2,956,095 is not directed to the use of any species such as isobutane for improving the catalyst life of a strong acid catalyst used in ultra low temperature isomerization.

U.S. Pat. No. 3,201,494 and U.S. Pat. No. 3,394,202 are also directed to ultra low temperature isomerization and are especially pertinent to the present invention.

U.S. Pat. No. 3,201,494 is directed to liquid phase isomerization of hydrocarbons using a hexafluoro-antimonic acid catalyst in hydrofluoric acid, which catalyst

is obtained, according to example 1 of the patent, by dissolving antimony pentafluoride in hydrofluoric acid.

U.S. Pat. No. 3,394,202 is also directed to isomerization also using an antimony fluoride-hydrochloric acid catalyst but in the U.S. Pat. No. 3,394,202 the catalyst is supported on a base such as fluorided alumina. According to U.S. Pat. No. 3,394,202,

"paraffin isomerization [with the supported antimony fluoride catalyst] is effected at about -10° to 60°C., preferably 10° to 50°C. In C₅-C₇ isomerization, the reaction rate may be increased appreciably by the addition of 5-25% w., isobutane, which does not participate in the reaction. Examples of other conversions which may be carried out with the present catalysts are described in copending application Ser. No. 284,806 [now U.S. Pat. No. 3,201,494], as discussed."

Gradual deactivation of the catalyst, which may occur because of presence of impurities in the feed or because of small amounts of polymerization products, may be suppressed by effecting the reaction in the presence of 1-3% m. hydrogen, based on the hydrocarbon feed. This hydrogen may be fed to the reactor as a gas, or may be partially or completely dissolved in the hydrocarbon feed."

Example 7 of U.S. Pat. No. 3,201,494 shows the acceleration of n-pentane isomerization by adding isobutane. As can be seen from Table III of the patent, no acceleration was obtained for isobutane contents above 9.2 wt. % in the feed. The highest isobutane content of any of the feeds isomerized in U.S. Pat. No. 3,201,494 was 22.8 wt. % isobutane for the feed in example VIII.

The feedstocks of the examples in U.S. Pat. No. 3,394,202 were n-pentane plus methylcyclopentane containing no isobutanes.

U.S. Pat. No. 3,394,202 discloses, as can be seen from the portion quoted above, without any exemplary data, that 5-25 wt. % isobutane may be used to increase the C₅-C₇ isomerization reaction rate. There is no enabling disclosure in either U.S. Pat. No. 3,394,202 or U.S. Pat. No. 3,201,494 that isobutane of any concentration is helpful to improve the stability of the antimony-pentafluoride catalyst system, nor is there any disclosure of improved stability of the catalyst system for isobutane contents above 25 wt. %.

SUMMARY

According to the present invention, in a process for isomerizing a C₅, C₆ or C₇ normal paraffin feed, which comprises contacting the feed with a catalyst comprising hydrofluoric acid-antimony pentafluoride supported on a porous solid support, and wherein the contacting is carried out at a low temperature between -10° and 400°F., the improvement is made which comprises reducing the deactivation rate of the catalyst by including sufficient isobutane in the feed so that the feed isobutane content is more than 25 wt %.

The paraffin feed which can be isomerized according to the process of the present invention includes at least one C₅, C₆ or C₇ normal paraffin and may contain other isomerizable paraffins such as cycloparaffins (sometimes referred to as naphthenes). The feedstocks to the process of the present invention will contain at least one normal paraffin, i.e., a C₅ through C₇ normal paraffin and may contain cycloparaffins as well as mixtures of C₅-C₇ normal paraffins. In the case of both normal paraffins and cycloparaffins, preferably only C₅ to C₁₂ paraffins are included in the feed. The most preferred

feedstocks to the process of the present invention are a C₅ and/or C₆ normal paraffin feed.

The catalyst used in the process of the present invention is HF-antimony pentafluoride. This catalyst is used in solid phase as HF-antimony pentafluoride on a porous solid support, most preferably fluorided alumina.

The temperature used in the process of the present invention is below 400°F., preferably below 150°F., and more preferably below 120°F.

The present invention is based largely on my discovery that isobutane dramatically reduces the deactivation rate of the strong acid catalyst, especially the hydrofluoric acid-antimony pentafluoride catalyst, used in the subject isomerization process. In my initial work on this system, using an HF-SbF₅ catalyst, I found a deactivation rate for the catalyst of about 0.02 (with the deactivation rate defined as the decrease of the logarithm of the fractional concentration of product isomer per hour). In an effort to reduce this deactivation rate, which is a high deactivation rate, I tried saturating the feed to the isomerization catalyst system with hydrogen. Using the hydrogen, I obtained a seven-fold reduction in catalyst deactivation rate. However, even this reduced deactivation rate was still a considerable rate so that the process had little commercial attraction. Subsequently, I tried using added hydrogen fluoride in addition to the saturation hydrogen, but instead of improving the deactivation rate, the deactivation rate for the isomerization of a normal pentane feedstock actually became higher, that is, worse. In still further experiments I found that methylcyclopentane, which of course contains a tertiary carbon atom, increased the deactivation rate when it was present in a normal pentane feedstock to the subject isomerization process.

After the above, I tried a normal pentane feedstock which contained isobutane in an amount of about 25 wt. %, and I surprisingly found a substantially lower deactivation rate than when feeding normal pentane without the isobutane in the normal pentane. I also noticed that lowering the feed benzene content considerably lowered the deactivation rate. However, taking out benzene is not sufficient to achieve a very low deactivation rate.

I then made a more dramatic unexpected finding in view of the prior art, which was that if the isobutane content in the feedstock was above at least about 25 wt. %, e.g., 40 wt. % isobutane, then the catalyst deactivation rate was almost nil for a purified paraffinic feed to the subject isomerization process. Furthermore, even for a feed that was not highly purified, e.g., a feed which contained benzene, isobutane at substantial levels such as above about 25 wt. % would dramatically reduce the deactivation rate of the antimony-pentafluoride catalyst system used in the present invention.

In the process of the present invention preferred amounts of isobutane in the paraffinic feedstock are 40 weight per cent and above, and 50 wt. % and above is particularly preferred. Particularly preferred temperature for the isomerization reaction in the present invention has been found to be in the range of about 30° to 80°F., more preferably 40°-70°F., as I have found that temperature above about 70°F., and especially above 80°F., can contribute to increased deactivation rate for the isomerization catalyst used in the present invention.

In the preferred isomerization process of the present invention, I have found that normal butane is isomerized to only a very slight extent (approximately nil) at the preferred isomerization temperatures which are

below about 80°F. At higher temperatures, for example 150°F. and higher, appreciable butane isomerization occurs.

My finding that isobutane in the feedstock, particularly above about 25 wt. %, is especially effective in reducing the deactivation rate was further confirmed by experiments in which substantially all conditions were held constant, except that the ratio of isobutane to normal butane in the hexane feedstock was varied. Thus, when the isobutane content was decreased the normal butane content was increased so that the total butane content of the feedstock remained constant. I found in these experiments that isobutane was especially effective in reducing the deactivation rate of the catalyst compared to the effectiveness of normal butane.

The hydrofluoric acid-antimony pentafluoride catalyst used in the present invention is supported on a porous solid inert support. By porous solid support is meant an inert support material having a porous structure and a surface area typically in the range of 1 to about 300 m²/gram or even higher. Preferably, the surface area will be in the range of about 1 to 100 m²/gram. The porous solid support of the invention typically has pore diameters ranging from 10 to 1000 Å.

The porous solid support of the subject invention is preferably selected from the inorganic oxide group consisting of alumina, zirconia, silica, silica-alumina, magnesia, chromia, boria, and mixtures and combinations thereof. Other porous solid supports may also be used such as natural and synthetic crystalline aluminasilicate zeolites, such as zeolite X, Y, mordenite, erionite, etc., as well as other natural materials such as bauxite, kieselguhr, kaolin, bentonite, diatomaceous earth and the like.

Particularly preferred porous solid supports are made from alumina or are alumina containing, e.g., fluorided alumina. I have found that fluoriding the alumina to a substantial extent so as to obtain 60 wt. % fluorine or more in the fluorided support results in an improved support for the HF-antimony pentafluoride compared to an alumina support which has only been mildly fluorided such as one which has been fluorided only on the most exterior surfaces of the alumina.

Other porous solid supports such as polytetrafluoroethylene, carbon, e.g., charcoal, polytrichlorofluoroethylene, and the like may also be used. Charcoal used as the porous solid support may have a surface area as high as 1200 m²/gram. Basically, the support should be substantially inert to HF-SbF₅ and insoluble in the mixture under isomerization reaction conditions. While the porous solid support may initially be reactive to

solid supports are coated with a thin layer of inert fluoride.

BRIEF DESCRIPTION OF THE DRAWINGS

The drawings are graphs showing the sharp decrease in deactivation rate of the isomerization catalyst used in the present invention when the isobutane content of the feed is increased to levels above about 25 wt. %.

DETAILED DESCRIPTION OF THE DRAWINGS

The ordinate of FIG. 1 shows the deactivation rate as the change in the log of the fractional concentration of the isomer products per unit time (per hour). The graph is based on isomerization of a normal pentane feedstock and the isomer products include 2-2-dimethyl butane, 2-3-dimethyl butane, 2-methyl pentane, and 3-methyl pentane. The abscissa in the drawing is the weight per cent isobutane in the normal hexane feedstock to the isomerization reaction zone.

The HF-antimony pentafluoride catalyst used to generate the data upon which FIG. 1 had a fluorided alumina porous solid support. The catalyst was prepared by treating fluorided alumina with HF-SbF₅. The HF-SbF₅ was prepared by adding anhydrous HF to liquid antimony pentafluoride.

The analysis of the catalyst was:

Treated alumina base	Catalpa alumina
Source	Catapal alumina
Wt.% of catalyst	60.8
Wt.% Fluorine	62.0
Surface area, m ² /g.	<10
Liquid Acid added	
Wt.% of catalyst	39.2
Wt.% SbF ₅	73.8
Wt.% HF	26.2

35

Table 2 summarizes the data upon which FIG. 1 is based. As can be seen from the table, the very low deactivation rate for 60% isobutane in the normal hexane feed was checked after the isobutane content of the feed had been lowered to 29.3% and was also checked after the isobutane had been lowered to 11.4%. Thus the data point in FIG. 1 at 60% isobutane in the feed has been checked severalfold to confirm the surprisingly low deactivation rate at 60% isobutane in the feed.

FIG. 1 shows that the deactivation rate for the catalyst used in the normal hexane isomerization run was 180 times worse, i.e., 180 times higher, for a normal hexane feed containing 11.4% isobutane compared to a normal hexane feed containing 60 % isobutane.

HF-SbF₅ the supports may be rendered inert by exposure to non-aqueous solutions of antimony pentafluoride and HF. Upon removal of the liquid, the porous

In another isomerization run the effect of using 2-methyl pentane was studied. 2-methyl pentane, of course, contains a tertiary carbon atom just as isobutane contains a tertiary carbon atom. However, I found

that when isomerizing normal hexane using about 60 wt. % 2-methyl pentane in the feed, there was a rapid decline in activity of the catalyst, that is, a rapid deactivation rate. The reaction conditions were substantially the same as in the case of feeding 60% isobutane-40% normal hexane as per Table 2 above, but in the case of the normal hexane feed containing 60% 2-methyl pentane the deactivation rate was at least 100 times greater than the deactivation rate when using the same amount of isobutane.

The ordinate of FIG. 2 shows the deactivation rate as the change in the log of the fractional concentration of the isomer products per unit time (per hour). The graph is based upon the isomerization of a normal hexane feedstock and the isomer products include 2-2-dimethyl butane, 2-3-dimethyl butane, 2-methyl pentane, and 3-methyl pentane. The abscissa in the drawing is the weight per cent isobutane in the normal hexane feedstock to the isomerization reaction zone.

Table 3 below summarizes the data upon which FIG. 2 is based.

Reaction conditions are summarized in the table. The table also shows at the bottom how the conversion of the normal hexane to isohexane products decreased as the run time progressed. As can be seen from the data at the bottom of the table and from the graph of this data, the deactivation rate of the catalyst dropped dramatically with increased isobutane content in the feed, especially for isobutane contents above about 25 wt. %.

What is claimed is:

1. In a process for isomerizing a paraffin feed comprising a C_5 , C_6 , or C_7 normal paraffin by contacting the feed with a catalyst comprising hydrofluoric acid-antimony pentafluoride supported on a porous solid support substantially inert to said hydrofluoric acid-antimony pentafluoride and wherein the contacting is carried out at a low temperature between -10° and $120^\circ F.$, the improvement which comprises reducing the deactivation rate of the catalyst by including sufficient isobutane in the feed so that the feed isobutane content is more than 25 wt. %.

2. A process in accordance with claim 1 wherein the

The catalyst used in run no. 125-140 was prepared by treating an alumina base with hydrofluoric acid to obtain a base containing 60.4 wt. % fluorine. The fluorided alumina base was then treated with a HF-SbF₅ liquid containing (based on materials used to form the liquid) 74.8 wt. % antimony pentafluoride and 25.1 % hydrofluoric acid. The HF-SbF₅ liquid was adsorbed into the porous structure of the fluorided alumina to obtain the final catalyst which can be described as a supported hydrofluoric acid-antimony hexafluoride catalyst. The catalysts in runs 125-141 and 125-142 were prepared in substantially the same manner.

isobutane content in the feed is more than 40 wt. %.

3. A process in accordance with claim 1 wherein the porous solid support is fluorided alumina containing at least 60 wt. % fluorine.

4. A process in accordance with claim 1 wherein the contacting is carried out at a temperature between about 30 $^\circ F$. and 80 $^\circ F$.

5. A process in accordance with claim 4 wherein said paraffin feed comprises a C_5 or C_6 normal paraffin.

6. A process in accordance with claim 1 wherein said paraffin feed comprises a C_5 or C_6 normal paraffin.
